UNITED STATES PATENT OFFICE.

FRANK W. ADSIT, OF MINNEAPOLIS, MINNESOTA, ASSIGNOR TO ADSIT GENERAL ELECTRIC COMPANY, OF MINNEAPOLIS, MINNESOTA, A CORPORATION OF MINNESOTA.

TELEPHONE-EXCHANGE APPARATUS.

1,217,080.

Specification of Letters Patent. Patented Feb. 20, 1917.

Application filed March 17, 1915. Serial No. 15,114.

To all whom it may concern:

Be it known that I, FRANK W. Adsit, a citizen of the United States, residing at Minneapolis, in the county of Hennepin and State of Minnesota, have invented new and useful Telephone-Exchange Apparatus, of which the following is a specification.

My invention relates to improvements in telephone exchange apparatus, of which the following is a full description, reference being had to the accompanying drawings forming a part of this specification.

My invention relates more particularly to means for controlling the duration of a telephone conversation and provides means whereby the conversation may be automatically interrupted and the circuits restored to the normal condition without supervision of the operator.

This invention is particularly well adapted to be used in connection with conversation originating from toll stations, and particularly such toll stations as are equipped with the ordinary class of coin boxes.

In the ordinary operation of such stations, it is the practice for a call to be put through in the following manner.

The party making the call at the coin box will first call the central operator in the ordinary manner and give the number of the party he wishes to talk with.

The operator uses her answering plug in answering the call, and with her calling plug makes a connection with the jack corresponding to the party wanted, and makes the call in the ordinary manner.

When the called party answers, the operator who is still supervising the line, tells the calling party to drop in the proper coin. When this is done, the operator is notified by suitable means, and allows the conversation to proceed.

The conversation may extend over an indefinite period and is ended only when the parties thereto hang their receivers on the hooks thus signaling the central operator who disconnects in the ordinary manner.

It is the growing practice of operating telephone companies to make their charges for telephone service in proportion to the amount the subscriber uses the telephone.

It has become apparent to the operating companies that the commodity they are selling to the public is time, and the true meas-

ure of service is the length of time the telephone apparatus is in use.

Attempts have been made to devise an equitable means of charging for service by putting in meters that would measure the number of calls on any particular telephone, but this system is faulty in that it does not take into account the length of time of the individual calls.

A more equitable system is that ordinarily used for long distance work where the charge is actually based on the length of time the lines are used.

While this system of charging is equitable, the method of handling it is cumbersome and expensive as it requires a great deal of supervision by the operator.

By means of my invention, the operating companies can sell their service on the basis of the time used, which is equitable, and furthermore the operation automatically gives the subscriber the exact length of conversation paid for, and at the same time minimizes the amount of supervision required by the operator.

In the accompanying drawing, is shown a common form of line circuit in which 5 represents the jack, 22 the cut off relay, 50 the line relay and 51 the line lamp.

The jack 2 would be wired to similar lamp and relays which for simplicity are omitted, as the action is well known to all skilled in the art. 56 and 57 are subscribers' sets of ordinary type.

The cord circuit shown in the drawing is of a common type ordinarily associated with the line circuit shown, except that my invention is added into the calling side of the cord circuit.

The answering side of the cord circuit operates in a manner known to the telephone art and for simplicity, a description is omitted.

A party making a call will signal the central operator in the usual manner (not shown) and the operator will insert her answering plug 1 into the jack 2 corresponding to the calling party, then by throwing the listening key 3 she connects in her set (not shown) in the ordinary manner and ascertains the number wanted.

She then inserts the calling plug 4 into the jack 5 corresponding to the desired party and rings the party by throwing the

ringing key 6, which connects the ringing current in the ordinary manner (not shown).

When the calling plug 4 is inserted into the jack 5, a circuit is established as follows:

From battery 7 through wires 8, 9, 10, supervisory lamp 11, wires 12, 13, and 14, contact 16, wire 17, operating coil 18, wire 10, 19, the sleeve of the calling plug 20, sleeve 15 of the jack 21, winding of cut-off relay 22 to the other side of the battery 7, which is grounded at 23. This lights the supervisory lamp 11 operates the cut-off relay 22 which clears the line signaling apparatus from that line in the usual manner and energizes the coil 18 whose armature 24 is prevented from operating by the latch 25.

When the called party answers, the battery 7 is fed out through the winding A—A' of the repeating coil, through the supervisory relay 26, through the key, plug, jack, line and subscriber's instrument in the ordinary manner.

25 The relay 26 being thus energized, a circuit is completed as follows:

From battery 7, wire 8, wire 52, relay contact 27, wire 28, key contact 29, operating coil 30, wire 31, wire 14, contact 16, wire 30 17, coil 18, wire 19, sleeve of plug 20, jack sleeve 21, coil 22, to the other side of battery which is grounded at 23.

This energizes the coil 30 which pulls the gear 31 into mesh with the constantly driven pinion 32. The gear 31 being carried on the supporting arm 34, which is pivoted at 33, will be normally held out of mesh with the pinion 32 by the spring 35. The coil 30 also serves to shunt the supervisory lamp 11 so it will be dark.

40 The pinion 32 which is constantly driven by any suitable method (not shown) now drives the gear 31 in an anticlock-wise direction, and this motion is continued for a 45 certain pre-determined time, which for the purpose of description, we will call five minutes.

Just before the expiration of the five minutes, possibly fifteen seconds, the arm 36 carried by the gear 31, lifts the spring 37, causing it to make contact at 38, which brings a tone signal from a tone test circuit 55, on to the established line circuit as follows:

55 Source of tone signal, wire 39, spring 37, contact 38, wire 40 to one side of the line back through the subscriber's loop to wire 41, contact 42, wire 43, to source of signal.

60 This tone signal in the subscriber's instrument, which of course is heard in both instruments, is to advise them the period of conversation for which the calling party has paid, is practically finished. They may then either terminate their conversation or 65 the calling party can signal the operator

and by paying a second time, obtain a second five minute talking period.

Should the parties continue talking, the arm 36 in its continued motion will strike the lower end of the latch lever 25, releasing 70 armature 24, which will be drawn up, thus opening the talking circuit between the two subscribers. This also opens the circuit of the supervisor relay 26, hence its armature is released and the contact at 27 is opened, 75 thus opening the circuit of operating coil 30, and the gear 31 is swung back to normal position by the spring 35 and the arm 36 is restored to normal position by the spring 53.

The supervisory lamp 11, which has been 80 shunted out during conversation by the coil 30, will now be illuminated, informing the operator the circuit has been dis-connected, and she can dis-connect her cords in the ordinary manner, unless the calling party signals her he wishes another five minute period. Should he do so, the operator can, by momentarily opening the key contact 16, release the armature 24 of the coil 18, putting it again under the control of the latch 25, 90 which again completes the circuit, drawing the gear 31 into mesh with the constantly driven pinion 32 and starting a second five minute period, which will be identical with the first.

95 Should the operator wish for any reason, such as in the case of a long distance call, to hold up the operation of the timing mechanism, she can do so by throwing the key 44 to connect in the resistance coil 45 in 100 place of the operating coil 30.

The supervision on the hanging up of either subscriber is standard and the timer is released by the opening of the contact 27 in the same manner when the receiver is 105 hung upon the hook as when the contact 24 is broken through the operation of coil 18 already described.

The act of withdrawing the plug 4 from the jack 5 restores the timer, as it opens all 110 the circuits thus releasing all of the mechanism. The restoring of the latch 25 to its normal position is clearly shown by the drawing through the action of the arm 36, which when returning to normal, presses 115 upon the lever 46 which is pivoted to the member 47, moving this member about its pivot 48 through pressure on the pin 49, and the other end of the lever 47 thrusts the stem 54 to the left, thus restoring the latch 120 25 and the armature 24 to their normal positions.

While in this specification and drawing, my invention is shown in connection with a certain cord circuit and associated with a 125 certain class of subscriber's line, it is evident the invention may be applied directly to various types of circuits used in the telephone and signaling field and I do not wish to be understood as confining myself to the ap- 130

lication or arrangement of parts as described.

Having described my invention, what I claim as new and desire to protect by Letters Patent is:

1. Telephone exchange apparatus comprising a line circuit, a subscriber's set, a cord circuit in the central station, adapted to coöperate with said line circuit, and means associated with said cord circuit, adapted to open the connection between said cord circuit and said line circuit at the end of a predetermined period.
2. In a telephone system, the combination of a cord circuit having an answering side and a calling side, a line circuit, timing mechanism having rotatable means controlled by the calling side of said cord circuit and means in the timing means for shutting off said timing means at the end of a predetermined period.
3. In a telephone system, the combination of a cord circuit having an answering side and a calling side, a line circuit, timing

mechanism having rotatable means controlled by the calling side of said cord circuit and means in the timing means for shutting off said timing means at the end of a predetermined period and a tone circuit including a contact closable by said timing means just prior to the shutting off of said timing means.

4. In a telephone system, the combination of a line circuit, a cord circuit having an answering side and a calling side, timing mechanism, electromagnetic starting means for said timing mechanism controllable by the electrical condition of the calling side of said cord circuit, a contact closable by said timing mechanism at the end of a predetermined period, a contact in the talking circuit of said cord circuit, electromagnetic means for opening said contact and mechanical means for preventing the operation of said electromagnetic means prior to the expiration of a certain predetermined period.

FRANK W. ADSIT.
